DESIGN FOR A BOTTLE OR SIMILAR CONTAINER

Edwin T. Reynolds, West Englewood, N. J., assignor to Lorr Laboratories, Inc., Paterson, N. J., a corporation of New Jersey

Application April 9, 1938, Serial No. 76,397

Term of patent 14 years

To all whom it may concern:

Be it known that I, Edwin T. Reynolds, a citizen of the United States of America, residing in West Englewood, Bergen County, New Jersey, have invented a new, original, and ornamental Design for a Bottle or Similar Container, of which the following is a specification, reference being had to the accompanying drawing, forming part thereof.

In the drawing:

I claim:

The ornamental design for a bottle or similar container substantially as shown.

EDWIN T. REYNOLDS.
